(57) **CLAIM**

The ornamental design for a fishing line stopper tool, as shown and described.

DESCRIPTION

FIG. 1 is a perspective view of a fishing line stopper tool according to the design herein.

FIG. 2 is a front view of the fishing line stopper tool shown in FIG. 1.

FIG. 3 is a rear view of the fishing line stopper tool shown in FIG. 1.

FIG. 4 is a right side view of the fishing line stopper tool shown in FIG. 1.

FIG. 5 is a left side view of the fishing line stopper tool shown in FIG. 1.

FIG. 6 is a top view of the fishing line stopper tool shown in FIG. 1.

FIG. 7 is a bottom view of the fishing line stopper tool shown in FIG. 1.

FIG. 8 is a perspective view of an alternative embodiment of fishing line stopper tool according to the design herein.

FIG. 9 is a front view of an alternative embodiment of the fishing line stopper tool shown in FIG. 8.

FIG. 10 is a rear view of an alternative embodiment of the fishing line stopper tool shown in FIG. 8.

FIG. 11 is a right side view of an alternative embodiment of the fishing line stopper tool shown in FIG. 8.

FIG. 12 is a left side view of an alternative embodiment of the fishing line stopper tool shown in FIG. 8.

FIG. 13 is a top view of an alternative embodiment of the fishing line stopper tool shown in FIG. 8; and,

FIG. 14 is a bottom view of an alternative embodiment of the fishing line stopper tool shown in FIG. 8.

The broken lines that are included in the figures of the drawings denote aspects of the tool that form no part of the claimed design.
